DEEP TEXTURED DECORATIVE LAMINATE

Jack August Willard, Hamilton, Ohio, assignor to Formica Corporation, Cincinnati, Ohio

Filed Aug. 29, 1972, Ser. No. 284,692

Term of patent 14 years

Int. Cl. D5—06

U.S. Cl. D87—3 G

The figure is a plan view of a deep textured decorative laminate showing my new design.

I claim:

The ornamental design for a deep textured decorative laminate, substantially as shown.
